UNITED STATES PATENT OFFICE

2,446,230

LIGHTING FIXTURE

Paul H. Irmischer, Chicago, Ill.

Application July 24, 1946, Serial No. 685,991

1 Claim. (Cl. 240—110)

1

This invention relates to certain new and useful improvements in a lighting fixture and has for its principal object the provision of an improved construction of this character, which will be highly efficient in use and economical in manufacture.

More particularly the invention relates to the shade of the lamp assembly. In this aspect of the invention, an object is to provide a lamp shade comprising relatively few parts and assembled in a manner such as requires no riveting, brazing, welding or the like.

The lamp construction shown in the accompanying drawings is what is known as a fluorescent lamp, which includes the usual fluorescent tube and a pull chain switch. As my invention is hereafter described and claimed, it will be apparent that the hood construction may be used with other types of bulbs, the object being to provide a shade, the parts of which may be expeditiously assembled by one other than a skilled mechanic, without the use of complicated tools and without the necessity of employing screws, solder, welding or the like.

Other objects will appear hereinafter.

The invention consists in the novel combination and arrangement of parts to be hereinafter described and claimed.

The invention will be best understood by reference to the accompanying drawings showing the preferred form of construction, and in which:

Fig. 1 is a perspective view of a lamp construction showing my improved shade associated therewith;

Fig. 2 is a sectional detail view taken substantially on line 2—2 of Fig. 3;

Fig. 3 is a fragmentary vertical cross sectional view of an end portion of the lamp shade; and

Fig. 4 is a fragmentary perspective view of the lamp shade parts in exploded relation with respect to each other.

The several objects of my invention are accomplished by the preferred form of construction as shown in the accompanying drawings.

For the purpose of illustration and explanation, I have shown my improved lamp shade associated with a fluorescent tube 10 of the standard construction and mounted within the shade 11 by means of suitable mounting brackets 12. These mounting brackets 12 and the lamp 10, as well as the pull chain switch, the chains of the latter being shown at 13, constitute no part of the present invention and, as stated, are shown for the purpose of illustration and explanation. My improved shade may be constructed for associa-

tion with lamps of different types other than fluorescent tubes.

This shade 11 may be of any shape or form, particularly the end thereof, without departing from the spirit of my invention.

The shade 11 includes a shield 14 formed from a sheet of material bent to provide an enclosure for the tube 10 with its opposite edge portions 15 spaced from each other to provide a light slot 16 of elongated formation.

Each end 17 of the shield 14 is provided with a transversely extending groove 18, the edge portion 19 of which provides a retaining flange 20.

The ends of the shield 14 are closed by caps 21 having a form corresponding to the shape of the end portion 17 of the shield 14 with which it is associated.

This cap 21 provides an end wall 22 having a perforation 23 through which the mounting bolt 24 of the bracket 12 is projected.

The cap 21 provides a lateral flange 25 adapted to snugly engage in the groove 18 and retained therein by the flange 20.

The shield 14 is formed of yieldable material so that when the flange 25 is mounted in the groove 18, the flange 25 will have yieldable contact with the shield 14.

The inner wall of the groove 18, as indicated at 26, is provided by a groove 27 formed in the shield 14 in the reverse direction to the groove 18. The longitudinal edge portions 15 of the shield 14 are turned inwardly upon the shield 14 to provide elongated flanges 27' which bear upon the ends 28 of the flange 25. A tie band is indicated at 29. This band 29 is formed of yieldable material and is of a width substantially equal to that of the groove 27. The end portions 30 of this tie band 29 are bent inwardly upon the flanges 27'.

From an inspection of Figures 2 and 4, it will be noted that the elongated flanges 27' are spaced from the adjacent wall portions 31 of the shield 14 for reasons hereinafter set forth.

When the shade 11 is completely assembled in the manner now to be described, there are attached to the mounting bolts 24 arms 32 formed as a part of brackets or hooks 33, which permit suspending or supporting the shade from a suitable support such as, for example, the head panel or end of a bed. These hooks normally are arranged to diverge from each other in a direction rearwardly of the shade so that when hooked upon an element of the bed, they will be yieldably urged toward each other to effect a bending upon

the bolts 24 whereby to frictionally hold the shade in an adjusted position.

To assemble the shade 11, the parts at the inception of the assembly operation are related one to the other in the manner shown in the exploded view, Fig. 4. The first step in the assembly operation is to spring apart the edge portions 15 of the shield 14 to permit the insertion or positioning of the flange 25 in the groove 18 between the retaining walls 20 and 26. The operator next positions the tie band 29 in the groove 27 and turns the ends 30 upon the flanges 27'. The final step consists in pressing the end portions 34 of the flanges 27' upon the end portions 28 of the flange 25, upon the completion of which operation the cap 21 is mounted in fixed relation with respect to the shield 14 and this is accomplished simply by the use of common pliers or light instrument, which instrument is used to press the end portions 34 of the flanges 27' upon the ends of the flange 25.

When the shade is assembled in this manner, the supporting brackets 33 and fluorescent tube brackets 12 and tube 10 are then arranged in their proper position with respect to the shade.

The tie band 29 essentially serves to ornament the opposite ends of the shade, and the same may be omitted if desired.

While I have illustrated and described the preferred form of construction for carrying my invention into effect, this is capable of variation and modifications without departing from the spirit of the invention. I, therefore, do not wish to be limited to the precise details of construction

set forth, but desire to avail myself of such variations and modifications as come within the scope of the appended claim.

Having thus described my invention, what I claim as new and desire to protect by Letters Patent is:

A lighting fixture comprising a shade formed from a sheet of material bent to provide a transversely curved shield having opposite longitudinal edges substantially spaced apart to provide a light slot and having said edge portions turned inwardly to provide oppositely disposed flanges, said shield having a retaining groove formed in each of its end portions, and end caps having peripheral portions insertable in the shield within in said grooves and with the peripheral portions of said caps arranged between the flanges and the shield, said flanges being pressed upon said peripheral portions of said caps to retain the peripheral portions of the caps within the grooves.

PAUL H. IRMISCHER.
